HENRY W. ALLEN, OF EARLYSVILLE, VIRGINIA.

METHOD OF AND APPARATUS FOR SEPARATING MINERALS.

1,301,532.

Specification of Letters Patent. Patented Apr. 22, 1919.

Application filed July 3, 1918. Serial No. 243,100.

To all whom it may concern:

Be it known that HENRY W. ALLEN, a citizen of the United States, residing at Earlysville, in the county of Albemarle and State 5 of Virginia, has invented a certain new and useful Method of and Apparatus for Separating Minerals, of which the following is a specification.

This invention relates in general to an 10 improved method of and apparatus for recovering minerals, and relates specifically to a process of separating mineral particles from the froth or foam employed in the so called "flotation" system to remove minerals 15 from the remainder of the ore, and to apparatus for effecting exploitation of the process.

The object of this invention is to provide 20 an efficient and simple method of separating the minerals from the froth or foam utilized in "flotation" to remove the minerals from the remainder of the ore, and to further provide simple, efficient and compact apparatus for exploiting the process commercially. 25 A more specific object is to provide a process and an apparatus whereby the mineral particles may be separated from the oil and wherein the separated oil is returned to its natural fluid condition without the 30 use of acids, thereby permitting direct re-utilization of the oil in the froth producing apparatus of the flotation system. These and other objects and advantages will be apparent from the description.

35 An example of one form of apparatus for commercially exploiting my invention is shown in the accompanying drawing which forms a part of this specification, and in which the various parts are designated by 40 suitable reference numerals.

Figure 1 is a top or plan view of the apparatus for automatically separating the mineral particles from the froth.

Fig. 2 is a diagrammatic sectional side- 45 elevation of the separating apparatus.

Fig. 3 is a longitudinal sectional view of the vacuum drum.

Fig. 4 is a longitudinal sectional view of one of the heating rollers.

50 In the specific form of the apparatus which I have illustrated in the drawing, the main elements are the froth supply tank or basin 2, the froth remover 3, the continuous or endless filtering medium 4, the froth 55 pressing or disintegrating rolls or rollers 5, the heating rolls or rollers 6, the vacuum

drum 7, the mineral removing brushes 8, 45 and the mineral deposit box 9. The froth 32 is supplied to the basin 2 from froth forming apparatus of construction well 60 known to those skilled in the art. The froth remover 3 consists of a pair of rollers 10 rotatably mounted in bearings 28 secured to the walls of the basin 2, an endless belt or band coacting with the rollers 10, and a 65 plurality of flights 27 secured to the endless band and adapted to skim the foam or froth off of the liquid in the basin 2.

The endless filtering medium 4 which may be a fine screen or gauze, coacts with end 70 rollers 33, 40 and passes successively between the sets of rollers 5, 6 and in contact with the vacuum drum 7. The pressing device or rollers 5 are rotatably mounted in suitable bearings, being geared together by 75 means of spur gears 19, 20. These rollers 5 are preferably covered with rubber or some other pliable substance and are mounted directly above a liquid catch basin 30 having a drain 34 leading to the froth forming apparatus. The heating rollers 6 are likewise rotatably mounted in suitable bearings, being geared together by means of spur gears 21. These rollers 6 are provided with interior chambers 31 as shown in Fig. 4, 80 85 which chambers communicate with a source of heat such as steam or hot gas through one of the conduits 24, 25 and exhaust the spent heating medium through the other conduit. 90

The vacuum drum 7 shown in Fig. 3, comprises an outer porous or perforated cylindrical shell, an inner cylindrical shell 41, and an intermediate cylindrical shell 42. The outer and the intermediate shells are 95 separated by an annular chamber 38 which is divided into four sections by means of radial partitions. The intermediate and inner shells 42, 41 are joined by means of radial pipes 37 which connect the annular chamber 38 with the interior of the inner shell 41. The outer, intermediate and inner shells are provided with end heads and are simultaneously rotatable about a stationary hollow cylindrical casing 44 by means of a 100 motor 22 drivingly associated with a spur gear 23 secured to an end head of the drum 7. The stationary casing 44 is provided with a lower elongated opening 35 and has a central hollow supporting shaft 26 mounted 105 upon pedestals 29. The interior of the shaft 26 communicates with the interior of the 110

casings 41, 44 through openings 36, and is connected to the suction side of a suitable pumping device. The end head of the drum 7 remote from the gear 23, is provided with 5 a pulley 15 which is drivingly connected with a pulley 14 on the shaft of one of the heating rollers 6 by means of a belt 18. The pulley 14 is drivingly connected with a pulley 13 on the shaft of one of the pressing 10 rollers 5 by means of a belt 17. The pulley 13 is drivingly connected with a pulley 12 on the shaft of one of the rollers 10 by means of a belt 16. It is of course not essential to utilize belts and pulleys to drivingly connect the various elements as any other driving means may be employed.

Engagement between the drum 7 and the filtering medium 4 is maintained by means of a series of rollers 39 mounted in suitable 20 end bearings. A mineral removing device or brush 8 engages the periphery of the drum 7 while a similar device or brush 45 engages the medium 4 adjacent the mineral discharge box 9.

25 During normal exploitation of the process, the froth is fed into the supply basin 2 from any suitable source and the apparatus is set in motion by operation of the motor 22. As the motor 22 revolves the drum 7 in an anti-clockwise direction as viewed in Fig. 2, the belts 18, 17 transmit this motion to the upper rollers 6, 5 respectively causing these rollers to rotate in like directions. The lower rollers 6, 5 being geared directly to the corresponding upper rollers, are rotated reversely. The motion of the upper roller 5 is transmitted through the belt 16 to the adjacent roller 10 causing this roller 10 to rotate in an anti-clockwise direction. The 30 endless bands coating with the various rollers are thus caused to travel in the directions indicated by the arrows in Fig. 2. The interiors of the rollers 6 are then supplied with heating medium and the shaft 26 is 35 connected to the pumping device.

40 As the flights or scrapers 27 travel over the basin 2, they skim the froth 32 off of the liquid in the basin 2 and deposit the same upon the traveling filtering medium 4. The filtering medium 4 conveys the froth 32 between the pressing rollers 5, which disintegrate the froth bubbles expressing the liquid and depositing the residue upon the filtering medium 4. The liquid passes 45 through the filtering medium 4 and flows into the catch basin 30 from whence it flows back to the froth producing apparatus for reutilization. The residues delivered from the pressing rollers 5 are next passed between the heating rollers 6 where they are dried by the application of heat. From the heating rollers 6, the residues are next passed along the periphery of the drum 7. Here air is drawn through the filtering 50 medium 4 and through the layer of residue

thereon, the air being drawn through the adjacent segment of the annular chamber 38, through the pipes 37, openings 35, 36 and interior of the shaft 26 and delivered to the vacuum pump. The residues are thus finally 70 and thoroughly dried by the flow of air therethrough. As the filtering medium continues its course the dried particles of residue or mineral are deposited by gravity into the collecting box 9. The particles of 75 mineral which adhere to the drum 7 are brushed off by the brush 8. The particles of mineral which adhere to the filtering medium 4 are brushed off by the brush 45. In this manner the mineral particles are effectively and automatically removed from the froth with the aid of very slight power consumption and within a limited floor space. The liquid or oil expressed from the froth 80 is returned to its natural state and may be reutilized in the froth forming apparatus.

85 By constructing the heating rollers as disclosed, any suitable heating medium may be employed without affecting the quality of the mineral. The opening 35 being of a 90 width substantially equal to one fourth of the length of the circumference of the support 44, and the medium 4 coating with substantially a like portion of the periphery of the drum 7, causes practically all of 95 the air sucked into the drum 7 to pass through the filtering medium 4.

90 It will be obvious that the apparatus may be altered within limits without affecting the efficiency thereof and of the method, and the present application is intended to cover 100 obvious modifications within the scope of the claims.

105 It is claimed and desired to protect by Letters Patent:—

1. The method of separating pulverulent material from froth, which comprises disintegrating the froth bubbles to liberate the air and to effect drainage of liquid therefrom, and treating the remaining solid constituents to produce a dry powder by subjecting the same to a reduced pressure.

110 2. The method of separating pulverulent material from froth, which comprises disintegrating the froth bubbles to liberate the air and to effect drainage of liquid therefrom, further drying the remaining solid constituents by heating, and finally treating the partially dried constituents to produce a dry powder by subjecting the same to a reduced pressure.

115 3. The method of separating pulverulent material from froth, which comprises skimming the froth from a bath of liquid, disintegrating the froth bubbles to liberate the air and to effect drainage of liquid therefrom, and treating the remaining solid constituents to produce a dry powder by subjecting the same to a reduced pressure.

120 4. The method of separating pulverulent

125

130

material from froth, which comprises skimming the froth from a bath of liquid, disintegrating the froth bubbles to liberate the air and to effect drainage of liquid therefrom, further drying the remaining solid constituents by heating and finally treating the partially dried constituents to produce a dry powder by subjecting the same to a reduced pressure.

5 10 5. In combination, a froth skimming device, a movable filter band adapted to receive froth from said device, a froth disintegrator coacting with said band, a vacuum producing device coacting with said band, and means for positively removing dried pulverulent material from said band and from said vacuum device.

15 20 6. In combination, a froth skimming device, a movable filter band adapted to receive froth from said device, and disintegrating, heating and vacuum producing devices coacting with said band in succession.

25 7. In combination, a froth supply device, an endless filter band adapted to receive froth from said device, disintegrating means, heating means, and vacuum produc-

ing means, said means respectively coacting with said band in succession.

8. In combination, a froth skimming device, an endless filter band adapted to receive froth from said device, a pair of disintegrating rolls coacting with said band, a pair of heating rolls coacting with said band, and a vacuum drum coacting with said band.

30 35 9. In combination, a froth skimming device, an endless filter band adjacent to said device, a disintegrating device coacting with said band, a vacuum producing device coacting with said band, and a single motor for imparting motion to all of said devices.

10. In combination, a froth skimming device, an endless filter band adjacent to said device, a pair of pressing rolls coacting with said band, a pair of heating rolls coacting with said band, a vacuum drum coacting with said band, and a single motor for transmitting motion to all of said elements.

40 45 In testimony whereof, the signature of the inventor is affixed hereto.

HENRY W. ALLEN.
